UNITED STATES PATENT OFFICE

168,858

TELEPHONE STAND OR SIMILAR ARTICLE

Elmer Rocker, Shaker Heights, Ohio

Application August 30, 1952, Serial No. 21,244

Term of patent 14 years

(CL. D33—14)

To all whom it may concern:

Be it known that I, Elmer Rocker, a citizen of the United States, residing at Shaker Heights, county of Cuyahoga and State of Ohio, have invented a new, original, and ornamental Design for a Telephone Stand or Similar Article, of which the following is a specification, reference being had to the accompanying drawing, forming a part thereof.

Fig. 1 is a front elevational view of a telephone stand or similar article, showing my new design;

Fig. 2 is a side elevational view thereof; and

Fig. 3 is a top plan view thereof.

I claim:

The ornamental design for a telephone stand or similar article, substantially as shown.

ELMER ROCKER.
